CAR COUPLER

Harry H. Wolfe, Columbus, Ohio, assignor to The Buckeye Steel Castings Company, Columbus, Ohio

Application March 15, 1948, Serial No. 15,020

8 Claims. (Cl. 213—148)

1. A railway car coupler comprising

The present invention relates to railway car couplers and more particularly pertains to anticreep means for the lock of such coupling devices.

The invention is directed to a railway car coupler having a pivoted knuckle and a substantially vertically movable lock for holding the knuckle in the closed position. In a coupler of this type, it is important to provide means for preventing undesired upward movement of the lock so as to avoid inadvertent unlocking of the knuckle. The prior art includes anticreep means in association with a lock of a car coupler and in one earlier arrangement, the lifter link is provided with an arm adapted to lie under a projection on the knuckle tail to serve as means for preventing upward movement of the lock. Such an anticreep arrangement has the disadvantage that when the knuckle rotates rearwardly in buff, the anticreep engagement between the arm and the projection on the knuckle tail is reduced to impair the security of the means for holding the lock in position to be engaged by locking surface on the knuckle tail.

It is an object of the present invention to provide more positive anticreep means in association with a car coupler which is independent of the knuckle so that any rearward rotation in buff or lateral movement of the knuckle tail will not reduce the area or scope of interengagement of the anticreep member with a ledge arranged in fixed relation on the coupler head whereby the anticreep member will more positively underlie the anticreep lug during all conditions of operation.

A further object of the invention is to provide a railway car coupler with anticreep means for the lock by engagement between a toggle or like means and a ledge or lug carried by the coupler head with such parts so constructed and arranged that if there is but slight overlap or interengagement of these elements resulting from movement of the rotary lever, further movement thereof will force the toggle into full anticreep engagement under the ledge.

A still further object of the invention is to provide a toggle in a car coupler of the type here under consideration which does not overlie the knuckle thrower arm before or after the lock is locked.

Another object of the invention is to so construct the toggle which serves as an anticreep member that no portion thereof will overlie the knuckle thrower arm during lifting of the lock to thereby avoid any tendency of the toggle to drag on the knuckle thrower arm tending to move

2. this member rearwardly and impairing attainment of a proper lockset engagement.

A more detailed object of the invention is to provide a ledge or lug on the coupler head adapted to be engaged by a uniquely shaped toggle to prevent accidental or undesired upward movement of the lock with the lug so constructed and positioned as to provide positive anticreep and at the same time facilitate the assembly of the coupler parts.

Other objects and features of the invention will be more apparent as the present disclosure proceeds and upon consideration of the following detailed description and the accompanying drawings wherein an exemplary embodiment of the invention is disclosed.

In the drawings:

Fig. 1 is a longitudinal sectional view of a portion of a coupler exhibiting the invention with the knuckle and rotary lever omitted and showing the lock in the locked position.

Fig. 2 is a similar sectional view showing the toggle in a rotated position freeing the toggle from anticreep engagement with the ledge on the coupler head.

Fig. 3 is a vertical sectional view of parts of the coupler showing the rotary lever in elevation with the lock raised and the toggle in engagement with the anticreep lug.

Fig. 4 is a sectional view taken on the vertical center line of the coupler with the lock on lockset with the section through the knuckle thrower arm taken on the line 4—4 of Fig. 8.

Fig. 5 is a similar sectional view showing the position of the lock and the rotary lever in full open position of the knuckle.

Fig. 6 is a sectional view taken on the horizontal center line of a coupler or on the line 6—6 of Fig. 1, with the parts in the same position as depicted in Fig. 3 and showing the zone of overlap between the toggle and the lug.

Fig. 7 is a sectional view taken on the horizontal center line of the coupler and illustrating the knuckle in the full open position with the parts in the position shown in Fig. 5.

Fig. 8 is a sectional view taken on the horizontal center line of the coupler showing the parts in lockset position of Fig. 4.

Fig. 9 is a side elevational view of the toggle.

Fig. 10 is an edge elevational view of the toggle.

Fig. 11 is a sectional view taken on the line 11—11 of Fig. 9.

Fig. 12 is an end view of the toggle.

Fig. 13 is a sectional view taken on the line 13—13 of Fig. 9.

Fig. 14 is a plan view of the rotor lever.
Fig. 15 is a side elevational view of the rotor lever.

The present invention is directed to anticreep means preventing undesired dislodgement of the lock from a position for being engaged by the locking face on the tail of the knuckle in a railway car coupler. The anticreep means includes a ledge or lug carried by the coupler head adapted to be engaged by the toggle. Accordingly, the anticreep means is independent of the knuckle and the knuckle tail. The ledge or lug is inclined with respect to a horizontal plane and is arcuate shaped and so constructed that if the toggle barely underlies the lug, the arcuate surfaces of the toggle and the lug are such as to increase the interengagement of these members particularly during surging of a car or upon oscillating movement of the rotor lever in response to such movements of the railway car.

Referring to the drawings, the coupler head is shown at 16. The coupler head is provided with a front opening 17 through which the tail 18 of the knuckle is adapted to extend. The knuckle is shown at 19 in Figs. 7 and 8 but is omitted from the other portions of the drawing for the purpose of more clearly illustrating the anticreep means. The knuckle is of conventional construction and is mounted for pivoting movement about a knuckle pivot pin 21. The coupler head 16 is provided with an opening or throat 22 for accommodating the lifting mechanism of the lock and the anticreep means. This opening is provided with a front wall 23 as shown in Figs. 1 and 3.

The coupler includes a lock 24 having a leg 26 which extends into the opening 22 in the locked position of the coupler. A knuckle thrower 27 is mounted for swinging movement about a trunnion 28 and the knuckle thrower includes a laterally arranged arm 29 as shown in Figs. 7 and 8. The knuckle thrower 27 is adapted to engage a surface 31 and turn the knuckle to an open position about the axis of knuckle pivot pin 21.

The leg portion 26 of the lock carries a trunnion 32 on which a toggle 33 is pivotally mounted. This toggle is shown more clearly in Fig. 9 and includes an arm 30 having an elongated slot 34 therein. This slot is hemi-circular shape at its ends and the center of the lower end of the slot is indicated at 36. The center for defining the arc of the upper end of the slot 34 is indicated at 37. The toggle 33 carries an arm 38 arranged substantially diametrically opposite the arm 30. This arm 38 is provided with an arcuate edge surface 39 having a curvature corresponding to the radius R, as shown in Fig. 3. The arm 38 of the toggle is also chamfered as shown at 41 in Figs. 8, 11 and 12 and the purpose of this angular arrangement will be more apparent as the present disclosure proceeds.

The toggle 33 is mounted for pivoted movement on the trunnion 32 so that this member is carried by the lower end of the leg 26 of the lock 24. The lock lifting mechanism includes a rotor lever 42 which is shown in Figs. 3, 5, 14 and 15 but is omitted from other parts of the drawings to facilitate illustration of the toggle and the anticreep features of the invention. A rivet or like means 43 extends through an arm of the rotor lever 42 and through the slot 34 in the toggle arm 30 as shown in Figs. 3 and 5. The rotor lever 42 is mounted for rotation on trunnion 44 carried by the coupler head. The axis of the rivet 43 is thereby adapted to move along an arc as indicated by the dash and dotted line 46 in Figs. 1,

5 and 4. An operating rod (not shown) is provided for engaging an eye on the rotor lever 42 and this operating rod extends to the side of the car where it is supported in a bracket and is employed for operating the coupler. The structure of the operating rod and the mounting thereof is conventional and well-understood in the art. Accordingly, an illustration thereof and a description of such a coupler operating mechanism appears unnecessary for a full understanding of the invention.

10 The present invention includes a lug or ledge 47 carried by the coupler head and overhanging the vertical wall 23 of the opening 22. This lug 15 may be cast integral with the coupler head 16 adjacent the front opening 17. The ledge or lug 47 serves as part of the anticreep means and the top surface thereof curves downwardly from the mouth of the opening 17 for facilitating introduction of the lock 24 into an operative position 20 in the coupler head. The under surface of the anticreep lug 47 is also of arcuate shape and has a radius of curvature indicated at R1 in Figs. 2 and 3. The purpose of curvature of the under 25 surface of the lug 47 and the arcuate surface 39 on the toggle will be more apparent from the following description of the operation of the anti-creep arrangement.

25 The locked position of the coupler is shown in Fig. 1. In this position of the parts, the center of the rivet 43 or the axis thereof then coincides with the center point 36 of the slot 34 and the toggle 33 is accordingly in the position shown in Fig. 1. In this position of the toggle, the arcuate surface 39 underlies the lug 47. As the rotor lever 42 is turned, it rotates about the axis of the trunnion 44 and the rivet 43 slides in the slot 34 until the axis of the rivet 43 coincides with the center point 37 at the top of the slot 34. The axis of the rivet 43 moves in the arcuate path 46 and upward movement of the rotor lever will swing the toggle 33 to the position shown in Fig. 2 where the center of the rivet 43 moving on the arc 46 coincides with an arc 51 defining the radius of the center point 37 with reference to the axis of the trunnion 32. The toggle 33 has then rotated on the trunnion 32 and the arcuate surface 39 of the toggle arm 38 is then in such a position as to be out from under the lug 47. This position of the toggle is shown in Fig. 2. The center point 36 of the slot 34 is located on the arc 46 when the upper end of the arm 38 of the toggle contacts the front wall 23 of the coupler head opening 22 as shown in Fig. 1. The center point 37 of the slot 34 is located on the arc 46 when the upper end of the arm 38 of the toggle is out from under the anticreep lug 47 as shown in Fig. 2. This construction provides a minimum of rotation or lost motion of the rotor lever 42 before initiating lifting of the lock 24.

60 When two couplers of the type herein described are mounted on railway cars and coupled in a train, there are times when the cars bounce and the train surges lengthwise simultaneously. During such a surge, when the cars tend to "bunch up," the knuckle 19 and the tail 18 release pressure on the lock 24 and the rotor lever 42 tends to rotate forward releasing the anticreep toggle 33 to a position as shown in Fig. 2. If the car is also bouncing, the lock 24 tends to jump up and if this member is raised sufficiently and onto a lockset position as shown in Fig. 4, the lock will remain elevated and the cars will separate when pull is again applied to the knuckle. The present invention provides a structure which

reduces such tendency of the cars to separate by unintentional release of the knuckle for movement to an unlocked position. A coupler exhibiting the invention requires a surge of the train of sufficient intensity to swing the rotor lever 42 for moving the toggle 33 to a position shown in Fig. 2 followed immediately by a bounce of sufficient intensity to throw the lock 24 to the lockset position shown in Fig. 4. Accordingly, the clearance C between the lip of the lug 47 and the upper end of the toggle arm 38 is made as small as possible to thereby provide a more positive anticreep arrangement to prevent the arm 38 of the toggle 33 from escaping from engagement with the lug or anticreep ledge 47.

As shown in Fig. 3, the radius R defining the curvature of the arcuate surface 39 on the arm 38 of the toggle coincides with the radius R₁ defining the arcuate surface of the under face of the anticreep lug or ledge 47. This interengagement of the toggle with the ledge prevents further upward movement of the lock 24. The zone of interengagement of the toggle arm 38 with the ledge or lug 47 is further illustrated in Fig. 6 where the zone of overlap is indicated by the shaded area Z. If there is bouncing and surging of a car in a train provided with a coupler of the type and structure herein described, the rotor lever 42 may swing forward so that the upper end of the arm 38 of the toggle may barely underlie the lug 47. The inclined arcuate surfaces formed to have a radius R₁ on the lug and a radius of R for the surface 39 of the toggle will tend to increase the overlap or anticreep engagement of the toggle with the lug until the centers of the radii R and R₁ coincide.

When the anticreep means is released as shown in Fig. 2, further rotation of the rotor lever 42 raises the lock 24. A lockset shelf 52 is provided on the leg portion 26 of the lock. When this shelf is above the knuckle thrower arm 29, the leg portion 26 of the lock will move backwardly due to the direction of the force then being applied to the trunnion 32 on the lower end of the lock leg 26. A release of the rotor lever 42 will then allow the lockset shelf 52 to rest on the knuckle thrower arm 29 as shown in Figs. 4 and 8, and the knuckle 19 may then be opened. The arm 38 of the toggle 33 is then in a position as indicated at 54 in Fig. 4, and no part of the toggle is arranged over the knuckle thrower arm 29. If the upper end of the toggle were to overlie the thrower arm, there is a tendency for the toggle to drag on the knuckle thrower and move this member rearwardly so as to impair the lockset engagement. Accordingly, one of the features of the invention pertains to avoiding movement of the toggle arm 38 to a position as indicated at 56 in Fig. 4 in order to obtain lockset.

If it is desired to swing the knuckle 19 to an open position further rotation is imparted to the rotor lever 42 which swings the toggle 33 with the upper end portion thereof into engagement with the knuckle thrower arm 29 so as to turn the knuckle thrower 27 about the axis of the pin 28. The forward end portion of the knuckle thrower then engages the surface 31 on the knuckle 19 and swings this member in a clockwise direction in Fig. 8 about the axis of the knuckle pivot pin 21. The lock moves upwardly and assumes a position as shown in Figs. 5 and 7 when the knuckle is moved to the open position. As hereinabove described, the arm 38 of the toggle 33 is chamfered as shown at 41 in Figs. 8 and 12. Thus, when the lock 24 is on lockset, the knuckle tail 18

will clear the toggle arm 38 when the knuckle 19 is being moved to the open position.

The coupler may be assembled by first inserting the knuckle thrower 27. Thereafter the lock lifter assembly comprising the rotor lever 42 and the toggle 33 are riveted together and hooked onto the trunnion 44. The toggle 33 is raised through the opening 22 in the bottom of the coupler head. The lock 24 is then introduced with the trunnion 32 being first inserted through the front opening 17. The trunnion 32 of the lock is then inserted into the hole 58 in the toggle 33. The lock 24 is then moved back into the coupler head and raised to the lockset position shown in Fig. 4. Thereafter the knuckle 19 and the knuckle pivot pin 21 are applied. The arcuate shape of the top of the lug 47 facilitates the introduction of the lock 24 through the front opening 17 and does not interfere with the assembly of the coupler parts.

The anticreep means is independent of the knuckle tail and in operation of the assembly there is no tendency of the anticreep means being rendered inoperative by rotation of the knuckle in buff as is the case when the anticreep ledge or lug is carried by the knuckle tail. The arcuate characteristics of the anticreep lug and the toggle of the present invention provide a structure which move these parts to a position where there is a greater zone of overlap during bouncing or shaking of the cars.

While the present invention has been illustrated as applied to a coupler of the interlocking type, the anticreep mechanism may be readily applied to any type of coupler such as the Association of American Railroads Standard Tightlock or Type E couplers. The invention may be applied to couplers of the wedge lock type in which the locking surfaces on the lock and knuckle tail are tapered and the invention is equally applicable to couplers wherein the lock and knuckle have vertically engaging surfaces. Such modifications and others may be made without departing from the spirit and scope of the invention as set forth in the appended claims.

What I claim and desire to secure by Letters Patent is:

1. In a car coupler, a coupler head, a knuckle mounted for pivoting movement on the coupler head, a vertically movable lock for said knuckle, a knuckle thrower including a lateral arm, a toggle including an arm mounted for pivoting movement on the lock, an anticreep lug carried by the coupler head overlying an end of the arm on the toggle in the lowermost position of the lock, means for raising the lock and rotating said toggle, a lockset shelf carried by the lock for engaging the lateral arm of the knuckle thrower, and said toggle arm being so constructed as to avoid overlying or engagement with the knuckle thrower arm prior to and during lockset of the lock.

2. In a car coupler, a coupler head, a knuckle including a knuckle tail mounted for pivoting movement on the coupler head, a vertically movable lock for said knuckle tail, operating means for raising said lock to unlock the knuckle, a toggle arm carried by said operating means, a lug carried by the coupler head overlying an end of the toggle arm in a locked position of the lock, said toggle arm being adapted to engage said lug to limit undesired upward movement of the lock and swingable to a position to escape said lug and permit upward movement of the lock, and said toggle arm being chamfered to permit the knuckle

tail to swing to a full unlocked position without engaging the toggle arm.

3. In a railway coupler of the knuckle type, a coupler head having a front opening therein, said coupler head having a throat extending downwardly from the front opening, a wall surface on the coupler head defining the forward boundary of said throat, a lock including a leg adapted to extend into said throat in the locked position thereof, a lug carried by the coupler head having an upper surface arching downwardly from a lower edge of the front opening and projecting rearwardly from said wall surface into said throat, an under surface on said lug substantially parallel with said upper surface, a rotor lever mounted for rotary movement on a lower portion of the coupler head, a toggle pivotally connected at one end to said rotary lever and at an intermediate portion to the leg of said lock, an arm carried by the toggle, an arcuate-shaped nose portion on the arm shaped to engage and conform to the curvature of the under surface of said lug to prevent upward movement of the lock.

4. In a railway coupler of the knuckle type, a coupler head having a front opening therein, said coupler head having a throat extending downwardly from the front opening, a substantially vertical wall surface on the coupler head defining a front boundary of said throat, a lock including a leg adapted to extend into said throat in the locked position thereof, a lug carried by the coupler head having an upper surface inclined downwardly from a lower edge of the front opening and projecting rearwardly from said wall surface into said throat, a concave under surface on said lug, a rotor lever mounted for rotary movement on a lower portion of the coupler head, a toggle pivotally connected at one end to said rotary lever, a trunnion carried by the lock leg extending through a circular opening in an intermediate portion of the toggle, a convex nose carried by the other end of the toggle for engaging the under surface of said lug to prevent upward movement of the lock.

5. In a railway car coupler of the knuckle type, a coupler head having a front opening therein, a wall on the coupler head defining the front of a generally vertical opening extending downwardly from said front opening, a lug carried by said wall arching downwardly from a lower edge of the front opening and projecting into said vertical opening, a concave under surface on said lug, a trunnion mounted on a lower portion of the coupler head rearwardly of said vertical opening, a rotor lever swingable about the axis of said trunnion, a toggle having a circular opening in the intermediate portion, a lock including a leg, a trunnion carried by the leg extending through the opening in the intermediate portion of the toggle, said toggle having a slot in the lower end thereof, a rivet extending through said slot connecting the toggle to the rotor lever, and a convex shaped nose carried by the other end of the toggle for engaging the under surface of the lug and preventing inadvertent upper movement of the lock.

6. In a railway coupler, a coupler head having a front opening therein, a knuckle including a tail mounted for pivoting movement on the cou-

pler head, said coupler head having a throat extending downwardly from the front opening, a substantially vertical wall surface on the coupler head defining a front boundary of said throat, a lock including a leg adapted to extend into said throat in the locked position thereof, a lug carried by the coupler head overhanging said vertical wall surface in said throat, an under surface on said lug arching downwardly into the throat from said wall surface, a rotor lever mounted for rotary movement on a lower portion of the coupler head, a toggle pivotally connected at one end to said rotor lever and at an intermediate part to the leg of said lock, an arcuate nose carried by a free end of the toggle for engaging the under surface of said lug to prevent upward movement of the lock, and said nose being chamfered to provide clearance for the knuckle tail upon movement of the knuckle to an open position while the toggle remains in a lock-set position.

7. In a railway car coupler, a coupler head, a knuckle mounted for pivoting movement on the coupler head, a vertically movable lock for said knuckle, a knuckle thrower mounted for swinging movement on the coupler head including a laterally arranged arm, a toggle mounted on the lock for movement therewith, an anticreep lug carried by the coupler head overlying an end of the toggle in the locked position of the lock, an arm forming a part of the toggle extending in a direction to engage said anticreep lug in the absence of rotation of the toggle, a rotor lever mounted on a lower portion of the coupler head for swinging said toggle and raising the lock, a lock-set shelf carried by the lock for engaging said laterally arranged arm of the knuckle thrower, said toggle arm being so angularly disposed in relation to the axis of rotation of the toggle as to escape said anticreep lug during initial raising of the lock and to lie in such a position as to avoid engagement with the knuckle thrower arm prior to and during lock-set of the lock.

8. An anticreep and lock lifter for a railway coupler of the knuckle type comprising, a toggle member having a circular opening in an intermediate portion thereof, an arm extending from the intermediate portion, a convex nose on said arm, a chamfered edge on the nose portion, and an arm extending in a generally opposite direction from the intermediate portion, and the last arm having an elongated slot therein.
